ATTORNEY

UNITED STATES PATENT OFFICE.

ROBERT E. DEACON, OF CLEVELAND, OHIO.

SAFETY KEY HOLDER.

Application filed June 17, 1926. Serial No. 116,584.

This invention relates to new and useful improvements in safety key holders providing means to be applied to the inner side of house and other doors for holding the key 5 in the lock at right angles to the key slot when the lock bolt is thrown locking the door, preventing unauthorized tampering with the lock from the outside of the door by turning and pushing the key out of the 10 lock and unlocking the lock with another key or other means. Another object is to provide a key holder readily adjustable to allow the key to be inserted or withdrawn from the lock. Other objects and features of the invention will be hereinafter pointed out and 15 described.

In the drawings:—

Fig. 1 is a fragmentary inside view of a house door showing the attachment applied 20 with the key holder positioned to allow the key to be inserted or removed from the lock.

Fig. 2 is a similar view showing the key positioned in the locked door lock at right angles to the key slot with the key handle held by the key holder, preventing the key 25 from being pushed out or turned from the outside of the door.

Fig. 3 is a plan view with the door knobs and knob shaft removed showing the key 30 and holder in the same position as in Fig. 2.

Fig. 4 is a side view of a bracket.

Fig. 5 is a side view of the key holder.

Referring specifically to the drawings, 35 indicates a portion of the inner side of a house door having an ordinary door lock 7 mounted therein at the door edge 6 with a latch 8, throw bolt 9, door knob 10 and key-hole 11.

The key holder attachment, adapted to be 40 mounted on the inner side 5' of the door 5, comprises a pair of spaced right and left hand supporting brackets 12 and 13 preferably of heavy sheet metal having vertical walls 14 tapering to the top as at 15 and tapering to the bottom as at 16. Spaced journal holes 17 and 18 are provided in walls 45 14. The top of the brackets 12 and 13 have inwardly bent supporting feet 19 with screw holes 20 and the lower ends of the brackets 50 are provided with inwardly bent supporting feet 21 with screw holes 22.

The key holder has a pair of arms 23 and 55 24 extending oppositely from a yoke 25 having a slot 26 therein and an enlarged side 27 with a spaced folded portion 28.

As shown in Fig. 1 the attachment brackets are equally spaced about the inner door knob 10 and secured to the door side 5' by screws 29 extending through holes 20 and 22 in feet 19 and 21 which are positioned to 60 span the lock body 7. The arms 23 and 24 are slidably and rotatably journaled in bracket holes 17.

To insert the key in the lock, the holder is pushed to the right butting against 65 bracket 13, positioning the slot 26 of yoke 25 opposite the keyhole 11 allowing the key 30 to be inserted through the keyhole 11 into the lock 7. Upon turning the key, thereby throwing the bolt 9 and locking the door, the 70 key handle 31 is held at right angles to the key slot 11 and the holder is turned horizontally and pushed to the left with the side 27 and folded portion 28 engaging the key handle 31 between. The yoke side 25' is 75 allowed to butt against bracket 12.

To release the key, the holder is pushed to the right disengaging the handle 30 allowing the key to be turned and withdrawn from the lock. 80

The attachment is simple in construction, easy to apply and may be economically manufactured.

While I have shown and described one embodiment of the invention, obviously various 85 changes in the details of construction may be made without departing from the spirit and scope of the appended claims.

I claim:—

1. A keyholder comprising a pair of brackets 90 adapted to be attached to the side of a door, and having bearing holes, and a holder having arms projecting into said holes, the holder being slidable and swingable between said brackets and having a folded portion 95 between which the key handle may be engaged and held.

2. A keyholder comprising a pair of brackets 100 adapted to be attached to the side of a door, and having bearing holes and a holder having arms projecting into said holes, the holder being slidable and swingable between said brackets and having a folded portion between which the key handle may be engaged and held, the holder having a slot 105 thru which the key may be inserted into the key hole.

3. A keyholder comprising a pair of brackets 110 adapted to be fastened to the side of a door at respectively opposite sides of a key

hole therein, said brackets having bearing holes therein, and a holder consisting of a piece of metal having arms slideable and swingable in the brackets, said piece of metal being located between the brackets and having a vertical slot adapted to be positioned opposite the key hole when shifted to one position, and also having a folded portion

adapted to be positioned opposite the key hole when shifted to another position and to engage the handle of a key in the key hole in such latter position.

In testimony whereof, I do affix my signature.

ROBERT E. DEACON.
